COMBINED STUDY CARREL AND STORAGE UNIT

Frank R. Torrey, 9805 Dallas Ave.,
Silver Spring, Md. 20901

Filed Feb. 19, 1971, Ser. No. 117,206

Term of patent 14 years

Int. Cl. D6—04

U.S. Cl. D6—190

FIG. 1

FIG. 4

FIG. 2

FIG. 3

FIG. 1 is a perspective view of a combined study carrel and storage unit, showing my new design;

FIG. 2 is a rear elevational view thereof;

FIG. 3 is a left side elevational view thereof, and

FIG. 4 is a right side elevational view thereof.

I claim:

The ornamental design for a combined study carrel and storage unit, as shown.
